UNITED STATES PATENT OFFICE.

WILLIAM LA HODNY, OF BUFFALO, NEW YORK.

POLISHING-MACHINE.

1,026,321.

Specification of Letters Patent.

Patented May 14, 1912.

Application filed October 9, 1911. Serial No. 653,493.

To all whom it may concern:

Be it known that I, WILLIAM LA HODNY, a citizen of the United States, residing at Buffalo, in the county of Erie and State 5 of New York, have invented a new and useful Improvement in Polishing-Machines, of which the following is a specification.

This invention relates to machines for polishing the beveled edges of glass plates 10 which are used for mirrors and other purposes.

Large plates of glass vary materially in thickness at different portions thereof, and smaller plates of supposedly the same gage 15 and quality also vary considerably in thickness and in hardness, or in other respects, so that in polishing the beveled edge of a large plate, or in simultaneously polishing beveled edges on a plurality of smaller 20 plates, it is impractical to employ, as has been heretofore suggested, a long polishing cylinder intended to work on the edge or edges throughout substantially the full length thereof. Many plates are broken by 25 reason of the unequal pressure on different portions of the plate or on different plates. Further, the beveled edges of the plates may be of varying curved and irregular 30 shapes and patterns, in which case a long polishing cylinder can not be made to conform to the variations and changes in the shape or pattern of the edge to be polished and will fail to properly and uniformly 35 polish the beveled edge throughout its length.

The primary object of this invention is to produce a rapid, efficient and practical machine for polishing the beveled edges of glass plates, which is adapted to operate 40 either upon a single large plate or simultaneously upon a plurality of smaller plates and to polish the beveled edges of plates of various shapes and patterns, and in which provision is made for regulating the action 45 of the polishing wheels as may be required by reason of the different thicknesses or inequalities in the different plates or different portions of the plate being operated upon.

50 While, as above indicated, the machine is primarily intended to be used for polishing the beveled edges of glass plates it is not necessarily limited to this use, as the same construction without substantial 55 change can be used for grinding or other purposes.

In the accompanying drawings, consist-

ing of four sheets: Figure 1 is a front elevation of a polishing machine embodying the invention. Fig. 2 is a fragmentary plan 60 view of a slightly modified construction. Fig. 3 is a side elevation of the machine shown in Fig. 1. Fig. 4 is a sectional elevation, on an enlarged scale, on line 4-4, Fig. 1, of the mechanism for adjusting the 65 polishing wheels. Fig. 5 is a sectional elevation thereof on line 5-5, Fig. 4. Fig. 6 is a fragmentary rear elevation of the 70 gearing for adjusting the polishing wheels. Fig. 7 is a transverse sectional elevation 75 of the machine, on an enlarged scale, on line 7-7, Fig. 1. Fig. 8 is a fragmentary section on an enlarged scale, on line 8-8, Fig. 1. Fig. 9 is a fragmentary longitudinal sectional elevation, on an enlarged 80 scale, showing the means for reciprocating the table. Fig. 10 is a sectional plan view thereof on line 10-10, Fig. 9. Fig. 11 is a fragmentary plan view showing one of the swinging frames which support the 85 polishing wheels. Fig. 12 is an enlarged plan view, partly in section, of one of the pivot bearings for the swinging polishing wheel frames.

Like reference characters refer to like 85 parts in the several figures.

A represents the stationary main frame or bed of the machine, and B a carriage which is supported and adapted to reciprocate horizontally sidewise of the machine 90 on the main frame. One or more supplemental carriages or slides is or are supported and adjustable horizontally fore and aft of the machine on the main carriage B. There are preferably at least two supplemental carriages or slides C C' which are independently adjustable on the carriage B, and each supports a work table on which the glass plate, the edge of which is to be 95 polished, is secured. The work tables D D' 100 lie side by side and are adapted to be tilted or adjusted vertically to the same or different planes to adapt them to form together a support for a single glass plate 105 which is too large for one table, or to support separate smaller plates.

A series of rotary polishing wheels E are mounted above the work tables, so that as the latter reciprocate with the carriage beneath the wheels, the rear edge or edges 110 of the glass plate or plates on the tables will be polished. The polishing wheels are independently adjustable toward and from the work so that the action of the several

wheels can be regulated as required, and means are provided for moving the several wheels simultaneously into and out of contact with the glass.

5 The main frame A may be of any suitable construction, that shown in the drawings having upright legs or stands *a* and a horizontal portion which is provided with longitudinal guide-ways in which correspondingly shaped guide rails *b* on the carriage B are seated and adapted to slide.

10 The carriage B shown consists of a rectangular skeleton frame provided with a pair of parallel transverse guide-ways *c c* 15 for each of the slides C C', which have side flanges *c' c'* entering these guide-ways. These slides C C' are adjustable independently of each other on the main carriage B.

The work tables D D' shown consist of 20 flat plates which are arranged side by side over the slides C C', each being hinged at its rear end at *d* (Fig. 3) in any suitable manner to one of the slides so that the front ends of the tables can be adjusted up or 25 down for holding a glass plate or plates in the required position to polish beveled edges of different inclinations. Each table is provided at its rear edge with a stop or holding strip *d'*, Fig. 7, for the glass plate. This 30 preferably consists of a strip of wood held between the rear of the table and a clamping bar *d*² and adapted to be adjusted upwardly to compensate for wear by screws *d*³ passing through the clamping bar. This 35 construction produces a very desirable stop. The stop strip has sufficient give to prevent injury to the edges of the glass plates, and when its projecting edge is cut or worn by the glass it can be readily adjusted by the 40 screws *d*³ or removed.

Any suitable means can be employed for reciprocating the carriage with the parts supported thereby beneath the polishing wheels. The means shown for this purpose 45 comprise a longitudinal reversible feed screw F which is suitably journaled in the main frame beneath the carriage and works in a nut in a hanger *f* depending from the carriage. The feed screw is provided at 50 one end with two tight pulleys *f' f*² and an interposed loose pulley *f*³, which are connected by straight and crossed belts *g g'*, Fig. 3, to pulleys *g*² on a horizontal drive shaft G which is suitably journaled in a 55 bearing on a part of the frame or bracket *g*³ projecting rearwardly and upwardly from the main frame, and is provided with a pulley *g*⁴ for a driving belt.

H, Figs. 1, 3 and 10, represents a reversing 60 arm which depends from the carriage B and slidably engages a horizontal reversing rod *h* between two adjustable collars or parts *h' h*² on the rod. This reversing rod is slidably supported by bearings *h*³ on the 65 main frame and is connected by a lever *h*⁴

to a belt shipper I having guide loops for the straight and cross belts *g g'*. When the feed screw is driven in one direction it will feed the carriage toward the right until the reversing arm H strikes the collar *h'* and shifts the belts *g g'* and thereby reverses the direction of rotation of the feed screw F. The screw will then feed the carriage to the left until the reversing arm H engages the other collar *h*² and again reverses the rotation of the feed screw, the carriage and parts carried thereby being thus reciprocated beneath the polishing wheels.

The slides C C' are adjusted rearwardly and forwardly on the carriage to move the work to and from the polishing wheels by suitable means, such as adjusting screws K K' which are journaled on the front part of the carriage and engage screw-threaded nuts or parts *k* secured to the slides C and 80 C'. The adjusting screws K K' are provided at their front ends with wheels *k*² *k*³, or other handles, for turning them. The adjusting screws can be operated to adjust the slides C C' to corresponding or different positions, as may be required.

Each work table is tilted or adjusted vertically in the machine shown in the drawings by screws L, Figs. 1 and 7, which are connected to the front portion of the table 95 and engage in threaded holes in worm wheels *l* which are held from endwise movement in suitable bearings *l*' on the slide C or C' which supports the table and are turned simultaneously by worms *l*³ on a 100 shaft *l*² journaled in bearings on the slide and provided at one end with a hand wheel or device *l*⁴ for turning it. One of the worms *l*³ is shown in Fig. 7.

The invention is not restricted to the particular devices described for adjusting the slides horizontally and the tables vertically, and other means can be employed for producing these adjustments.

The several wheels E, which are intended 110 to polish the previously beveled edges of the glass plates, are secured to shafts *n* journaled in the free front ends of separate bearing frames or supports N which are pivotally mounted at their rear ends to 115 swing up and down independently of each other about the axis of a longitudinal shaft *n'* from which the wheels E are driven and which is preferably journaled in bearings *n*² on the frame bracket *g*³. The bearing frames may be pivoted on the machine in any suitable manner, but are preferably journaled on pivots *n*³ which are secured to the frame bracket *g*³ and which are provided with a central hole through which the 125 shaft *n'* passes. These pivots, being concentric with the shaft, permit the frames N to swing about the axis of the shaft and at the same time relieve the shaft *n'* of the strain that would be caused by pivotally mounting 130

the brackets directly on the shaft. The polishing wheels are driven by suitable means which permit the described up and down movement of the wheels, for instance, by 5 sprocket chains O passing around sprocket wheels secured on the shafts n and n'. The shaft n' can be driven in any suitable way, for instance, it is geared at one end by wheels p p' to one end of a main drive shaft 10 P, which is journaled in bearings on the frame bracket g³ and is provided at its opposite end with pulleys p² for a drive belt. The swinging support or frame N for each of the polishing wheels E is provided 15 with a depending arm or portion having a toothed segment Q meshing with a gear segment q which is secured in any suitable manner to a worm segment q' meshing with a worm q² on an adjusting shaft q³ which is 20 journaled in the main frame and extends to the front of the machine. The gear segment q and worm segment q' are preferably adjustable with regard to each other. In the construction shown, the worm segment 25 q' is rigidly secured to or formed with a hub or sleeve q⁴ and the gear segment q is formed with a split collar q⁵, which is adjustable circumferentially on the hub or sleeve q⁴, to which it is adapted to be rigidly 30 clamped by a bolt q⁶ or other device. The gear segment can thus be adjusted with regard to the worm segment to compensate for the wearing away of the polishing wheel, and smaller gear segments can be used than 35 which would be necessary if the segments were not adjustable. The hubs or sleeves q⁴ of the worm segments are preferably sleeved on a common horizontal bearing shaft q⁷, which is mounted at its ends on the frame bracket 40 g³, the worm segments being held from endwise movement on the shaft by collars or stops q⁸.

Means are preferably provided for operating the pivoted frames on which the 45 polishing wheels are mounted so that the wheels can be adjusted toward and from the work independently of each other, or so that all, or a part of the wheels can be adjusted simultaneously. In the construction shown in Fig. 1, all of the wheels are 50 adapted to be moved simultaneously, as follows: To the front end of each adjusting shaft q³ is secured a hand wheel or device R for turning the shaft, and this hand wheel 55 has a hub r on which a gear r' is splined to move lengthwise of the hub. The several gears r' are adapted, when moved rearwardly on the hubs, to mesh with a rack bar r² which is slidable lengthwise of the 60 machine in a suitable guide-way r³ secured to the main frame. When the gears r' are moved into engagement with the rack bar, the several adjusting shafts q³ will be simultaneously turned by the movement of the 65 rack bar. The rack bar can be moved by

any suitable means, such, for instance, as a crank S to which is secured a gear s which meshes with the rack bar. The crank is journaled on a stud s' secured to the frame of the machine. Adjustable means are preferably provided for stopping the movement of the rack bar in order to limit, as desired, the movement of the polishing wheels toward the work and prevent an operative from forcing the wheels E onto the work 70 with sufficient pressure to injure the same. Stops are shown for this purpose, comprising a projection s² formed on the crank S and adapted to strike projections s³ formed on a plate s⁴ which is adjustable 75 circumferentially with regard to the crank S. The plate is provided with a slot s⁵ through which a bolt s⁶ passes for clamping the plate s⁴ in any adjusted position. By suitably adjusting the plate s⁴, the downward movement of the wheels E toward the 80 work can be limited as desired.

It may be desirable, when simultaneously polishing a plurality of small plates in which only a few wheels are required for 85 each plate, to operate the wheels in groups so that the several wheels of each group can be adjusted simultaneously with each other but independently of the other group. This can be accomplished by making the 90 rack bar in sections T T', as shown in Fig. 2, and providing separate operating cranks t t' for the rack sections. Each section of the rack bar controls those polishing wheels which are connected therewith independently of the other wheels, and either group of wheels can be operated independently of the other group. The machine can thus be used as two smaller machines. If desired, the overlapping adjacent ends of the sections of the rack bar can be connected by 95 a pin t² to cause both sections to move together. The rack bar can then be operated by either of the cranks, whichever is most convenient for adjusting all of the polishing 100 wheels simultaneously.

In the operation of the machine for polishing beveled edges, one or more glass plates are secured on the work tables D D' with the edge or edges thereof to be polished 115 next to the polishing wheels and against the stops d'. The slides C C' are adjusted rearwardly by the screws K K' to move the beveled rear edges of the glass plate or plates against the polishing wheels, and the front edges of the work tables D D' are also adjusted up or down by means of the adjusting shafts l² to cause the polishing wheels to bear properly on the beveled faces. These adjustments enable plates to be set 120 so that the wheels will operate properly on bevels of different inclinations. One or more plates can be secured on each table, or if a single plate too large to be placed on one table is to be operated upon, the tables 125 130

can be adjusted to the same plane and the plate placed so as to rest on both tables. The machine is then started and the carriage B reciprocates, moving the plate or 5 plates to and fro beneath the polishing wheels which thus polish all portions of the rear edge or edges of the plate or plates. The polishing wheels can be caused to bear on the glass with the pressure necessary to 10 properly polish the beveled edge or edges, and this pressure can be regulated from time to time as required, as the polishing proceeds, by turning the wheel adjusting shafts q^3 . As the wheels are independently ad- 15 justable, each wheel can be set or adjusted to suit the particular condition of the plate, or portion of the plate, upon which it operates. Thus a uniform pressure of the wheels on all portions of the beveled edge or edges 20 can be effected notwithstanding that the plate may not be of uniform thickness throughout, or that different plates being polished may be of different thicknesses or of different quality of glass, while, on the 25 contrary, if different plates or different portions of a plate require different pressures of the wheels to uniformly polish them, this can be secured by independently adjusting the wheels, without danger of breaking or 30 injuring a plate, which would result if a single long cylinder were employed. The wheels can be pressed against the work with sufficient force to cause the yielding rims of the wheels to flatten out enough to bear on 35 a flat or plane beveled edge throughout the width thereof, so that the machine is adapted for polishing either plane or concaved bevel. If it is desired to move two or more of the wheels E to and from the work 40 simultaneously, the gears r , after each of the polishing wheels E has been adjusted toward the work as described, can be moved into engagement with the rack bar, and the wheels E can then be moved toward and 45 from the work by the crank S, or the cranks T T'.

The carriages are adjustable toward and from the wheels and also at an inclination to properly position the glass with reference to the wheels, but the automatic reciprocation or movement of the tables during the polishing or grinding operation is in a direction transversely to the planes of rotation of the wheels, so as to move the 50 edge being operated upon across the peripheries of the wheel, at an angle to the direction of motion thereof, instead of in a direction toward and from the wheels. This arrangement insures better work and prevents the possibility of feeding the glass 55 against the wheels with an injurious pressure.

The machine can be used for polishing the beveled surfaces of plates having curved 60 or irregular edges. When the machine is

used for this purpose, only one of the wheels is generally used, the other wheels being raised out of the way, and the table is adjusted backwardly and forwardly according to the contour of the edge to be polished.

By using a plurality of independently adjustable polishing wheels, each wheel can be adjusted with regard to that portion of the plate upon which it operates, and as large plates frequently vary considerably in thickness at different parts of the plate, the wheels can be adjusted accordingly and a uniform polish can be obtained throughout the length of the plate. This is also true where several small plates are to be 75 polished at the same time as these plates are liable to vary in thickness and the polishing wheels can be accommodated to such variations. Another advantage in using these wheels is that the portions of the plate between the wheels can cool off before being again traversed by the polishing wheels, thereby preventing excessive heating, and consequently cracking of plates.

I claim as my invention:

1. In a machine of the character described, the combination of a horizontally-reciprocating carriage, a slide which is adjustable on the carriage in a direction at an angle to the direction of movement of the carriage, a work table which is supported by said slide and is adjustable thereon to a position parallel with or inclined to the plane of said slide, a plurality of wheels which are mounted near one edge of said work table to move independently of each other toward and from the work table, means for driving said wheels, and means for regulating the pressure of said wheels on the work independently of each other, substantially as set forth.

2. In a machine of the character described, the combination of a horizontally-reciprocating carriage, a plurality of slides which are adjustable on the carriage in a direction at an angle to the direction of movement of the carriage, means for independently adjusting said slides, a work table supported by each of said slides, means for independently adjusting said work tables to positions parallel with or at an angle to the plane of said slides, a plurality of wheels which are mounted near one edge of said work tables to move toward and from the work tables, means for driving said wheels, and means for adjusting the wheel for each table toward and from the table independently of the wheel for the other table, substantially as set forth.

3. In a machine of the character described, the combination of a horizontally-reciprocating carriage, a slide which is adjustable forwardly and rearwardly on said carriage, a work table which is supported by said slide and is adjustable thereon to a

- position parallel with or inclined to the plane of said slide, a plurality of wheels which are mounted side by side parallel with each other in independently movable frames at the rear portion of the machine, means for driving said wheels, and means for adjusting said wheel frames independently to regulate the pressure of said wheels on the work, substantially as set forth.
- 5 4. In a machine of the character described, the combination of a plurality of driven rotary wheels mounted side by side to move up and down independently of each other, a work support, means for reciprocating the work support in a direction at an angle to the direction of rotation of the wheels, means for adjusting said work support toward and from said wheels and also to a position parallel with or inclined to the plane of reciprocation of the work support, and means for independently regulating the pressure of said wheels on the work, substantially as set forth.
- 10 5. In a machine of the character described, the combination of a horizontally reciprocating carriage, a slide adjustable laterally thereon and adapted to support the glass plate, a plurality of wheels mounted side by side parallel to each other in independently movable frames at the rear portion of the machine, means for driving said wheels, and means for reciprocating said carriage in a direction across the grinding surfaces of said wheels a distance slightly greater than the distance between two wheels, substantially as set forth.
- 15 6. In a machine of the character described, the combination of a plurality of driven rotary wheels mounted side by side, a work support, means for reciprocating the work support in a direction transverse to the planes of rotation of said wheels a distance slightly greater than the distance between two wheels, and means for moving said wheels independently of each other toward and from said work support, substantially as set forth.
- 20 7. In a machine of the character described, the combination of a plurality of driven rotary wheels mounted side by side, a carriage which is adapted to reciprocate in a direction transverse to the plane of rotation of said wheels, a plurality of work supports mounted on said carriage and adapted to be adjusted independently of each other with reference to said wheels, and means for adjusting the wheels adjacent to one work support independently of the wheels adjacent to the other work support, substantially as set forth.
- 25 8. In a machine of the character described, the combination of a work support, means for reciprocating said work support, a plurality of driven rotary wheels, means for adjusting said wheels independently of each other toward and from said work support, and means for moving a number of said wheels simultaneously toward and from said work support, substantially as set forth.
- 30 9. In a machine of the character described, the combination of a work support, means for reciprocating said work support, a plurality of driven rotary wheels which are journaled in frames pivoted to said machine, gear segments on said frames, gears with which said segments mesh to swing the frames on their pivots and adjust said wheels toward and from said work support, a gear connected with and adapted to turn said first mentioned gear, and means for actuating said second gear, substantially as set forth.
- 35 10. In a machine of the character described, the combination of a work support, means for reciprocating said work support, a plurality of driven rotary wheels which are journaled in frames pivoted to said machine, gear segments on said frames, gears with which said segments mesh to swing the frames on their pivots and adjust said wheels toward and from said work support, a gear connected with and adapted to turn said first mentioned gear, and means for actuating said second gear, substantially as set forth.
- 40 11. In a machine of the character described, the combination of a work support, means for reciprocating said work support, a plurality of driven rotary wheels which are journaled in frames pivoted to said machine, gear segments on said frames, gears with which said segments mesh to swing the frames on their pivots and adjust said wheels toward and from said work support, a gear connected with and adapted to turn said first mentioned gear, and means for actuating said second gear, said second gear and said first mentioned gear being adjustable with regard to each other, substantially as set forth.
- 45 12. In a machine of the character described, the combination of a reciprocating work support, a plurality of wheels mounted side by side parallel to each other, means for adjusting said work support and said wheels relative to each other, a stop strip against which the work can be placed and which projects above the surface of the work support adjacent to said wheels, and means for adjusting said strip with regard to the surface of said work support, substantially as set forth.
- 50 Witness my hand, this 7th day of October, 1911.
